DES. 2263

John Mc Barnes of Brooklyn, N.Y.

Letters Patent No. 33,63-Dated July 13-1866

Design for a Door Lock.

The schedule referred to in these Letters Patent and making part of the same,

to all whom it may concern:

Be it known that I, John Mc Barnes, of Brooklyn, N.Y., in the County of Kings and State of New York, have invented and secured a new and original design for Door locks and Latches and do hereby declare that the following is a full, clear and exact description thereof, reference being had to the accompanying drawings and to the letters of the characters marked thereon, and making a part of this specification.

The object or purpose of my invention is to give to the case and nosing or stryker of a door lock, or if a case, latch, an ornamental or artistic form, whereby such locks and latches will be relieved from the monotony and sameness and absence of beauty and necessity incident to the rectangular shape such articles have heretofore borne. Such ornamental or artistic form can also be equally well given to such locks as are adapted to be fixed to a door in but one position, or with but one side out, for to such locks are known as "Janus-faced" and capable of being applied to any door, either side out, as preferred.

The character of my invention consists in giving to the narrow sides or edges of the entire lock or latch, of both case and stryker, a configuration or outline bounded by a made up substance of curved or scalloped lines and surfaces, substantially as represented in the drawings. The front and back plates of the case, and the front plate of the nosing or stryker are also to be shaped to correspond with the contour or outline of such edges.

In the drawings A represents one of the narrow sides of the lock case, and B, the similar side of the stryker. The sides D and F, of the lock case though not shown in the perspective drawings, are shaped respectively like A and B. The edge of the plate C, and of the other plate on the opposite side of the lock case, are also shaped so as to correspond with the form of the sides A, B, D. The outer or form of the sides A, D and that of the other sides B and E may be also transposed if desired.

The corners of the case and stryker are also cut off as represented in the drawing.

It will be at once apparent that such a novel con-
figuration can be given to a simple latch, so called, in which there is
only a latch and one bolt and also to dead bolts, so called, having one
latch, but only a bolt and such bolt operated by the key without any
knob.

What I claim as my invention and desire to secure by Letters Patent is

The design for a rim door lock or latch, substantially as represented, that is, in which the narrow sides of the case and stryker, and the edges of the front and back plates, are bounded by curved or scalloped lines, and the corners of the case and stryker cut off substantially as described.

Witness:

G. D. Law,

Bracei, Conn.
